CLAIM

The ornamental design for an intravaginal device, substantially as shown and described.

DESCRIPTION

FIG. 1 is a front and left side perspective view of an intravaginal device embodying the claimed design;

FIG. 2 is an enlarged front view of the intravaginal device of FIG. 1;

FIG. 3 is an enlarged rear view of the intravaginal device of FIG. 1;

FIG. 4 is a top view of the intravaginal device of FIG. 1;

FIG. 5 is a bottom view of the intravaginal device of FIG. 1;

FIG. 6 is a right side view of the intravaginal device of FIG. 1;

FIG. 7 is a left side view of the intravaginal device of FIG. 1;

FIG. 8 is a front and left side perspective view of a case, in a closed position, containing the intravaginal device shown in FIG. 1;

FIG. 9 is an exploded view of the case of FIG. 8 and the intravaginal device of FIG. 1;

FIG. 10 is a front and left side perspective view of a partially opened case containing the intravaginal device shown in FIG. 1;

FIG. 11 is an enlarged front view of a case containing the intravaginal device shown in FIG. 8;

FIG. 12 is an enlarged rear view of the case containing the intravaginal device shown in FIG. 8;

FIG. 13 is a right side view of the case and intravaginal device shown in FIG. 10;

FIG. 14 is a left side view of the case and intravaginal device shown in FIG. 10;

FIG. 15 is a top view of the case and intravaginal device shown in FIG. 10; and,

FIG. 16 is a bottom view of the case and intravaginal device shown in FIG. 10.

The broken lines show portions of the intravaginal device that form no part of the claimed design. The case shown in broken lines depicts environment and forms no part of the claimed design.
